HOPPER CONSTRUCTION

Filed Aug. 7, 1924

UNITED STATES PATENT OFFICE

FRANK B. ALLEN, OF LOWER MERION TOWNSHIP, MONTGOMERY COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

HOPPER CONSTRUCTION

Application filed August 7, 1924. Serial No. 730,611.

This invention relates to hopper construction and particularly to a gate for a hopper having a bottom discharge opening.

It also relates to certain improvements of the gate structures disclosed in my copending applications, Serial Nos. 571,404, filed July 28, 1922, and 683,792, filed December 31, 1923 now Patent No. 1,547,284, issued July 28, 1925.

10 In the drawings accompanying and forming a part of this specification.

Figure 1 is a vertical section taken along the line 1—1 of Fig. 2 of a hopper having a bottom discharge opening and provided 15 with a gate embodying certain features of my present invention.

Figure 2 is a longitudinal vertical section of the door and frame taken on line 2—2 of Fig. 1.

20 Fig. 3 is a top plan view of the door and stationary trough taken upon the line 3—3 of Fig. 1.

Figure 4 is a vertical sectional view taken on line 4—4 of Fig. 3, and

25 Figures 5 and 6 are, respectively, sectional views taken on lines 5—5 and 6—6 of Fig. 2 on a reduced scale.

Referring to the drawings, in which I have illustrated one form of gate, 1 designates as 30 an entirety a fragmentary portion of a hopper provided with a bottom discharge opening and equipped with a gate consisting of a frame 26 and a door 27 connected to the hopper and adapted to control the discharge 35 of liquid and solid material through the hopper discharge opening. The frame 26 consists of a plate 28 substantially rectangular in plan view to correspond with the shape of the hopper and provided with a central

40 opening coinciding with the discharge opening of the hopper. From the inner edges of the plate 28 I provide depending flanges 29 of substantially the same depth. The frame 26 may be connected to the hopper by various means but in this instance it is connected thereto by being secured to side members 30, and cross members 31 which are connected to the side members 30.

Door 27 consists of a body portion 32 and 45 flanges and associated body parts now to be

described. Rollers 33 secured to the rear end of the body portion 32, and rollers 34 secured to the forward end thereof by means of brackets 35, serve to support the door 27 in position to cooperate with the frame 26, in this instance by engagement with flanges 36 on or connected to the side members 30. A rear end liquid intercepting flange 37 preferably formed integral with the body portion 32 of the door extends upwardly well above the 50 top of the body portion and has a top surface which is inclined rearwardly and upwardly to such a level above the body portion as will prevent passage of liquid from the body portion thereover. On each side 55 of the door 27 I provide an open topped, straight, liquid carrying trough 38 preferably disposed in the horizontal plane of the door and each provided with a rear end wall 39 having a rearwardly and upwardly inclined top surface, the walls 39, as herein illustrated, being integral with flange 37. These troughs 38 are located outwardly of the depending flanges 29 on the frame 26, it being observed from Fig. 1 that these flanges 60 29 are in substantial alignment vertically with the upstanding flanges 40 constituting a part of the body portion 32 of the door 27. For a purpose which will presently appear, the outer walls 41 of the troughs 38 extend 65 above the top of the bottom portion 32 of the door and above the bottom of the adjacent depending flanges 29 on the frame 26. At the front end of the door is provided a forwardly projecting horizontal liquid discharge flange 70 42 adapted to discharge liquid therefrom into a suitable stationary trough 43.

When the gate is in operation, solid material is retained in the hopper by the door 27 when it is in closed position with respect 75 to the bottom opening of the hopper but liquid may pass freely through the hopper opening and be collected and discharged by the door into a drainage system. The liquid intercepting flange 37 extending along the 80 rear end of the door 27 being sufficiently high to prevent escape of liquid thereover, intercepts liquid flowing to that end of the door and directs it into the troughs 38 or back 85 toward the front end of the door. Means are 90

provided for insuring that all liquid intercepted by the flange 37 will be diverted in this manner, this means consisting, in the modification of the device herein shown, of liquid intercepting and diverting side flanges 5 44 preferably formed integral with walls 41 and flange 37, and of substantially the same height above the body portion 32 as flange 37. These flanges 44 extend from the flange 37 forwardly to a point well beyond the rear end walls 39 of the troughs 38 and may gradually diminish in height toward the front end of the door as shown. Water flowing toward the troughs 38 will be intercepted by the arrangement of overlapping walls comprising depending flanges 29 on the frame and the outer walls 41 of the troughs 38 on the door and diverted into troughs 38 where it will be collected and conducted to the forward end of the door and there discharged into the stationary trough 43.

It will be observed that the door illustrated is provided with a fluid directing flange along the rear end of the door to turn 25 all liquid therefrom toward the side or stationary troughs. This flange as well as the inclined rear end wall of the side troughs has a rearwardly and upwardly inclined top surface over which ashes or solid material may 30 be forced by depending parts when the door is moved into closed position. It will be understood that the normal clearance between the door and depending frame parts, such as flange 29, is always filled with ashes, 35 some of which may be scraped toward the rear of the door as it closes. Unless some means is provided, such as the inclination of the top surface of the flange 39, these ashes would tend eventually to pack in the space 40 between flanges 37 and 29 and prevent complete closing of the door.

It has been found that the rear end trough of doors of this general type tended to become filled with ashes scraped from the top 45 of the door by the depending rear end flange of the frame and that it was difficult to remove such accumulations of ashes from the trough manually and nearly impossible to do so mechanically. By my present construction, however, I completely avoid the 50 previous difficulties and provide a door embodying the desirable features as set forth hereinabove.

Solid material, such as ashes, accumulating 55 in the side troughs may be removed by any suitable positive fluid, mechanical or manual means as desired. Little or no attention is thus required to maintain the door in operative water collecting condition.

Although I have shown my present improvements of a gate frame in connection with one form of door, it will be understood by those skilled in the art that these herein described improvements can also be employed with many other forms of door. 65

Having thus described my invention so that those skilled in the art may practice the same, what I desire to secure by Letters Patent is defined in what is claimed.

What is claimed is:

1. In combination with a hopper having a bottom discharge opening, a frame surrounding the opening and connected to the hopper and provided with depending flanges adjacent to the inner edges thereof, and a 70 movable door cooperating when in closed position with the frame to prevent the discharge of solid material through the opening while providing for the free escape of liquid therethrough, the door having a flange across its rear end inclined rearwardly and extending well above the top of the body portion of the door, and a trough on each side of the door located approximately in the horizontal plane of the door and extending from adjacent to the rear end of the door to the front end thereof, the said troughs cooperating with the said flange to receive liquid intercepted by the flange, and a trough adjacent to the front end of the door adapted to receive liquid from the door.

2. A door for a hopper having a bottom opening comprising a body portion, a rearwardly inclined liquid intercepting flange extending upwardly well above the body portion from adjacent to the top of the body portion and a liquid collecting and conducting trough extending lengthwise of the door at each side thereof and adapted to receive liquid intercepted by the said flange, the rear 95 end wall of each said side trough being inclined rearwardly and upwardly to a height substantially equal to said flange.

3. A door for a hopper having a bottom opening comprising a body portion, a rearwardly inclined liquid intercepting flange extending upwardly well above the body portion from adjacent to the top of the body portion, troughs extending along the sides of the door and adapted to collect liquid from the top of said door, liquid intercepting and directing flanges extending forwardly from the rear flange to points in front of the rear ends of the said troughs to direct liquid into the troughs, the rear ends of the said troughs 100 being inclined upwardly and rearwardly.

4. A door for a hopper having a bottom opening comprising a body portion a rearwardly inclined flange extending upwardly 110 well above the body portion from adjacent to the top of the body portion, open topped mechanically cleanable liquid collecting and conducting side troughs adapted to receive liquid from the top of the said door and conduct it to the front end of the door, and liquid intercepting and directing side flanges extending forwardly from the ends of the rear flange to a point in front of the rear ends of the side troughs, the rear end wall of 115 120 125 130

each said side trough being inclined rearwardly and upwardly.

5. A gate for a hopper having a bottom opening comprising a frame surrounding the opening and having flanges depending therefrom adjacent to the several sides of the said opening; and a door cooperating with the frame and having a body portion, a liquid intercepting end flange at the rear end of the door extending well above the top of the body portion and having an upwardly and outwardly inclined top surface, open topped liquid collecting and conducting side troughs on opposite sides of the door disposed outside the adjacent depending flanges of the frame and having upwardly and outwardly inclined rear end walls adjacent to the said end flange, means on the door for intercepting liquid passing through the hopper discharge opening and directing it into the said troughs, a horizontal forwardly extending liquid discharge flange at the front end of the door and a stationary liquid receiving trough adapted to receive liquid from the troughs and horizontal flange.

6. A door for a hopper having a bottom opening comprising a body portion, a rear end liquid intercepting flange extending well above the top of the said body portion and having a rearwardly inclined top surface, open topped troughs on opposite sides of the door, the rear end wall of each trough having a rearwardly and upwardly inclined top surface, and a horizontal forwardly extending liquid discharging flange at the front end of the door.

7. A door for a hopper having a bottom opening comprising a body portion, a rear end liquid intercepting flange extending well above the top of the said body portion and having a rearwardly inclined top surface, open topped troughs on opposite sides of the door, the rear end wall of each trough merging into and being integral with the said rear end flange and having a rearwardly and upwardly inclined top surface, and a horizontal forwardly extending liquid discharging flange at the front end of the door.

In testimony whereof I hereunto affix my signature this twenty-eighth day of July, 1924.

FRANK B. ALLEN.
